UNITED STATES PATENT OFFICE.

MARSHALL B. GARDNER, OF AURORA, ILLINOIS, ASSIGNOR TO INTERNATIONAL CORSET COMPANY, OF AURORA, ILLINOIS, A CORPORATION OF ILLINOIS.

CORSET-CLASP.

1,278,134.

Specification of Letters Patent. Patented Sept. 10, 1918.

Application filed November 22, 1917, Serial No. 203,294. Renewed July 25, 1918. Serial No. 246,779.

To all whom it may concern:

Be it known that I, MARSHALL B. GARDNER, a citizen of the United States, and a resident of Aurora, in the county of Kane 5 and State of Illinois, have invented certain new and useful Improvements in Corset-Clasps; and I do hereby declare that the following is a full, clear, and exact description thereof, reference being had to the accompanying drawings, and to the letters of 10 reference marked thereon, which form a part of this specification.

This invention relates to improvements in corset clasps and consists of the matters 15 hereinafter described and more particularly pointed out in the appended claims.

The object of my invention is to provide an improved corset clasp which will so connect and hold the clasp stays of a corset together as to prevent buckling or tilting of 20 the stays and the resulting gaping between them, with its attendant discomfort to the wearer.

The advantages of my invention will appear as I proceed with my specification.

In the drawings:

Figure 1 is a perspective view of a corset to which my improved clasps have been applied.

30 Fig. 2 illustrates on an enlarged scale, a fragmentary part in front elevation of the two clasp stays with the clasp parts applied, and with the two parts of the clasp in position as when attached.

35 Fig. 3 is a view similar to Fig. 2, but with the stays and clasp parts in the position as they appear when being engaged or disengaged.

Fig. 4 is a view representing a transverse 40 section through Fig. 2 in a plane indicated by the line 4—4 of Fig. 2.

Fig. 5 is a view representing a transverse section through Fig. 3 in a plane indicated by the line 5—5 of Fig. 3.

45 Fig. 6 represents in side elevation on a still greater scale, a view of one of the clasp members.

Referring now in detail to that embodiment of my invention illustrated in the accompanying drawings:—10 indicates the corset body which opens in front where are attached the clasp members. 11, 12 indicate the stiffening strips or stays at the respective sides of the opening in the front of 55 the corset body.

The clasp in each case, comprises as usual, a loop or eyelet member 13 fixed to the stay or stiffening strip at one margin of the corset body, and a stud 14 fixed to the stay at the other margin of the corset body.

60 The eyelet member 13 has a key hole slot 15 comprising a comparatively large hole 16 and a narrower slot 17 opening into said hole. The stud 14 has a body 18, a head 19, and a rivet shank 20,—the latter being the means by which it is attached to the clasp stay 12.

65 The body and head, 18 and 19, are in the form of a mushroom with the head projecting beyond the body and inclined to the vertical axis of the body in a direction toward the opening between the two parts of the corset body. The head 14 is substantially larger than the slot part 17 of the eyelet member, and is nearly but not quite so 70 large as the hole 16 of said member. In other words, it is of a size such that it may be easily slipped through said hole. One side, 19^a, of the head, namely, the side farthest away from the corset opening, is 75 rounded transversely, while the opposite side is straight and has a bottom edge 19^b extending at right angles to the length of the slot 15 of the eyelet member 13. The edge 19^b of the stud head is adapted for engagement 80 at its ends in grooves 21 at the sides of the hole 16 in the eyelet member. The body 18 of the stud is oval, that is to say, elongated in cross-section and diametrically opposite the edge 19^b of the stud head, the said body 85 is provided with an enlargement at its base. The body 18 thus presents a comparatively large base to bear upon its stay transversely of the width of the stay, so that when riveted thereto it will be held rigidly against 90 rocking movement with respect to the stay.

95 The parts are constructed to operate as follows. When the eyelet and stud members are attached to their respective stays and the stays themselves are fixed to the usual 100 members of the corset body, being thus inclosed in a part of the corset fabric, the clasp members may be engaged, first one and then the other, down the length of the corset body in the usual fashion, by first 105 inserting the head of the stud through the larger part of the opening of the eyelet, namely the hole 16. The stud is then drawn either by the hand of the wearer, or by the natural expansion of the body, from the 110

larger hole opening 16 toward the narrower slot opening 17. When the stud has been fully drawn home to the end of the eyelet opening, the head flange 19^b will engage in the notches 21, 21 on the eyelet member. As will be manifest from a consideration of Fig. 4, this will result in an absolute lock of the stud to the eyelet member, which will not only prevent the corset from opening, but will also prevent throughout the length of the two stays, and particularly in the location of each clasp, a rocking or tilting movement of one stay with respect to the other stay.

15 It will be apparent to those familiar with the art that the improved clasp will not become disengaged in the ordinary movements of the wearer as in the case of the familiar clasp devices heretofore provided for corsets, 20 and also that the improved clasp will perform the additional function of preventing tilting or buckling between the clasp stays, to obviate which other attachments in addition to the clasps have heretofore 25 been applied to corset stays.

I claim as my invention:

1. A clasp of the kind described, comprising an eyelet member and a stud member, the eyelet member having a key hole 30 slot, and the stud member consisting of a body of comparatively large cross-section in a direction transverse of the stay to which it is to be attached, and of a head inclined downwardly and provided with a 35 flange adapted for engagement with the eyelet member when the clasp members are in locked position.

2. A clasp of the kind described, comprising an eyelet member having a key hole slot, and a stud member having a body elongated in cross section, a rivet shank at its bottom end and a comparatively large head at its top end, said head being inclined downwardly in one direction and being provided with a flange adapted for engagement with the eyelet member when the clasp members are in locked position, and the eyelet member being provided at each side of the slot with grooves adapted to be engaged by said flange in said locked position.

3. A clasp of the kind described, comprising an eyelet member having a key hole slot, and a stud member having a body elongated in cross section, said body being enlarged at one side of its base, having a rivet shank at its bottom end and having a comparatively large head at its top end, said head being inclined downwardly in one direction and being provided with a flange adapted for engagement with the eyelet member when the clasp members are in locked position, and the eyelet member being provided at each side of the slot with grooves adapted to be engaged by said flange in said locked position.

In testimony that I claim the foregoing as my invention I affix my signature in the presence of two witnesses, this 15 day of November, A. D. 1917.

MARSHALL B. GARDNER.
